UNITED STATES PATENT OFFICE.

WILLIAM LAWRENCE SAUNDERS, OF NORTH PLAINFIELD, NEW JERSEY.

AIR LIFT-PUMP.

SPECIFICATION forming part of Letters Patent No. 597,023, dated January 11, 1898.

Application filed May 2, 1896. Serial No. 590,053. (No model.)

To all whom it may concern:

Be it known that I, WILLIAM LAWRENCE SAUNDERS, a citizen of the United States, residing at North Plainfield, in the county of 5 Somerset and State of New Jersey, have invented certain new and useful Improvements in Air Lift-Pumps, of which the following is a description, reference being had to the accompanying drawings, and to the letters of 10 reference marked thereon.

My invention relates to improvements in the art of raising liquids by means of compressed air; and it consists in an improved process and apparatus whereby alternate 15 charges of water and compressed air are delivered to the eduction-pipe at a high initial velocity.

The object of the invention is to accomplish the elevation of water or other liquids 20 by means of compressed air or other gases with greater economy than has heretofore been possible.

In accordance with my invention the compressed air is not directed into the water in 25 the form of fine streams or jets which would readily commingle therewith, nor is it delivered continuously at the foot of the eduction-pipe, thereby, as asserted by some, dividing the water into piston-like layers the existence 30 of which is doubted, nor is either the air or the water started on its upward journey through the eduction or delivery pipe in a continuous stream; but by means of the arrangement of apparatus and the proper regulation 35 of the pressures of the liquid and the gas employed it is so arranged that masses of the liquid and masses of the gas are started up the delivery-pipe in alternation and each with a high velocity, as will appear. Whether 40 the gases and the liquid become more or less intimately commingled before leaving the delivery-pipe is immaterial so long as they start up the delivery-pipe with a sufficiently-high initial velocity, for it necessarily follows that 45 if so started and the supply of air and water in alternation be maintained with sufficient frequency the velocity of the inflow will communicate itself to the rising column, and as the same rises the superincumbent pressure 50 will be reduced and the masses of compressed gas by expansion will assist in the expulsion of the liquid above them.

It is to be understood that according to my invention compressed gases of almost any character may be employed and liquids of 55 any kind may be elevated by means thereof. For convenience I will hereinafter refer to them as compressed air and water.

In the accompanying drawings, Figure 1 is a view in elevation, showing an air-compressor, 60 an air-reservoir, and in section a well equipped according to my invention. Fig. 2 is a sectional elevation showing a slightly-modified arrangement.

A is an air-compressor engine of any suitable type.

B is a tank for receiving and holding the compressed air from A. Pipe a connects the cylinder of the air-compressor with the tank B. The tank B is provided with a safety-valve b.

C is the well to be pumped, which may be of any type sufficiently large in diameter to accommodate my apparatus.

D is a delivery-pipe, which where drilled 75 wells are used will vary in size according to the diameter of the well and in the case of a large well may be of any desired capacity.

E is a device which I have termed a "pressure-chamber," which is in the present instance shown as being supported at its lower end upon legs e, resting on the bottom of the well, although it may be supported from above if preferred.

The pressure-chamber E is larger in diameter than the delivery-pipe D and extends a short distance below the lower end of said delivery-pipe. The pressure-chamber is open at its lower end to permit the free ingress of water and is closed at its upper end around the delivery-pipe D, so that there is no escape of air at this point. Compressed air is supplied to the upper end of the pressure-chamber through pipe F, extending from the tank B and provided with a stop-cock f.

The lower end of the pressure-chamber E and also of the delivery-pipe D should be considerably below the level of the water in the well, which is indicated by the line X X.

Where the invention is applied to a drilled well which is provided with a metallic or other air-tight casing, as indicated in Fig. 2, the pressure-chamber E, as a separate construction, can be omitted and the casing of the well

used in place thereof, the space between the casing C' and the delivery-pipe D' constituting a pressure-chamber E'. This arrangement simplifies the apparatus and enables me 5 to use a larger pump in a well of given size. In said Fig. 2, C' is the permanent casing of the well. D' is the delivery-pipe. f' indicates the air-tight joint provided between the delivery-pipe and the casing at or above the 10 surface of the ground and completing the pressure-chamber E'. F is the air-pipe extending from the tank B. X X is the normal water-level. G G H H are the lines between which, or approximately between which, the 15 water-line will rise and fall or pulsate, due to the irrepressible conflict between the momentum of the water flowing into the pressure-chamber from the veins supplying the same, the opposing pressure of the compressed 20 air, and the constant variation of pressure caused by the escape of a portion of each alternately through the delivery-pipe.

Normally the water will stand in the pressure-chamber and in the delivery-pipe at, for 25 example, the level indicated by the line X X, Figs. 1 and 2. When, however, compressed air is admitted to the upper end of the pressure-chamber E or E' by opening the cock f, which is left open so long as the apparatus is 30 in operation, the water will be forced down in the same, and if the pressure of air is sufficient it will be forced down and back into the well or into the veins from whence it came until it reaches or almost reaches the line G 35 G', when the air will escape up the delivery-pipe D. The escape of air will lower the pressure in the pressure-chamber, whereupon the water will rise; but since the inflow of air is not checked mechanically the pressure in the 40 chamber E or E' will increase until the rise of the water is checked at a point above the exit or lower end of the pipe D—say at about the line H H—when the supply of compressed air from the tank B in the chamber E will check 45 the rise of water and again drive it down until the excess of air-pressure escapes through the delivery-pipe as before, when, just as soon as this happens, the water will again rise until stopped by the pressure in the chamber E or E'. 50 Each time the water rises in the pressure-chamber due to its momentum under the head of the water in the well a portion thereof will pass into the delivery-pipe, and for the purpose of causing the water which enters the 55 eduction or delivery pipe to do so with the highest initial velocity I have contracted the pipe near its lower end for a short distance to form a venturi, so that the momentum of the water rising therethrough will give increased velocity to the portion entering the 60 pipe, thereby adding to its upward-moving force and to the force with which the water will be drawn toward and into the delivery-pipe. The air-pressure now increasing sufficiently to drive the water down below the 65 foot of the delivery-pipe D or D', or to the line G G, permits a portion of the compressed

air to also enter the delivery-pipe D, which it does in the rear of the mass of water which had previously entered, forcing the same up 70 the delivery-pipe, and in view of the fact that the water entered as a solid body the compressed air following the same will have a solid body to act upon, and therefore it cannot escape except by driving the body of water immediately above it and those above that up the delivery-pipe. 75

The supply of air from the tank B will be continuous and of course must be maintained in said tank at a pressure in excess of the 80 pressure necessary to overcome the momentum of the water rising in the pressure-chamber under the head of the well, and so long as the supply of compressed air is maintained and there is sufficient water in the well the water and air will pulsate up and down in the pressure-chamber above and below the delivery-pipe, and alternate masses of each will escape into the delivery-pipe and be forced to the surface. 85

Modifications may be made in the construction and arrangement of the apparatus consistent with the foregoing description without departing from the invention.

Having now described my invention, what I claim is— 90

1. The herein-described method of pumping which consists in supplying directly to the open lower end of a valveless delivery-pipe surrounded by an open-bottom chamber 100 continuously supplied with a gas under pressure, of charges of the liquid and of the gas under pressure and in alternation.

2. The method of pumping which consists in supplying to the open lower end of a valveless delivery-pipe surrounded by a submerged pressure-chamber having its lower end permanently open to receive the liquid and continuously supplied with a gas under pressure, of charges of liquid and of gas at a high velocity and in alternation. 105

3. In a pumping operation the process of raising liquid which consists in supplying to a pressure-chamber permanently open at its lower end to receive the liquid, and provided 115 with a downwardly-extending delivery-pipe also open at its lower end said lower end located near the opening of the chamber, of compressed air at a point near the upper end of the pressure-chamber from a constant 120 source of supply, admitting liquid to the open end of the chamber and of the delivery-pipe under sufficient momentum to force itself into the delivery-pipe and also to cause an increase of the pressure of the compressed air 125 in the upper part of the chamber, until the momentum of the water entering the chamber is overcome thereby, when the water is forced down and out of the chamber into the well and the excess of air-pressure allowed to 130 escape up the delivery-pipe forcing the water before it and vice versa.

4. The combination with a well to be pumped, of a delivery-pipe, the lower end of

- which is open to receive the water and which extends below the normal water-level, a pressure-chamber surrounding said delivery-pipe, and permanently open at its lower end to receive the water, connections between the upper part of the pressure-chamber and an independent source of compressed air or other gas, whereby, under the variations of pressure in the chamber due to the momentum of the head of water and the escape of part of its contents, the air and water will pulsate above and below the mouth or exit of the delivery-pipe, and portions escape thereinto alternately.
- 5 5. The combination with a well, of a pressure-chamber closed at its upper end and permanently open at its lower end to permit free inflow of water, of a delivery-pipe arranged within the pressure-chamber and extending below the normal water-level, and open at its lower end to receive the water from the well, and an independent source of compressed gas connected with the upper end of the pressure-chamber, whereby under a constant flow 25 of gas under pressure from the independent source into the pressure-chamber the gas and liquid will pulsate about the lower end or mouth of the delivery-pipe, alternately entering the same.
- 20 6. In an air lift-pump the combination of a delivery-pipe extending below the normal water-level, a pressure-chamber inclosing part of said delivery-pipe and extending down below the lower or inlet end thereof, and permanently open at its lower end to receive the water, connections between the upper part of
- the pressure-chamber and an independent supply of air under pressure, and means for regulating the pressure of air supplied to the pressure-chamber.
- 40 7. In an air lift-pump the combination of a stationary delivery-pipe formed with a contracted portion near its lower extremity, a pressure-chamber surrounding said pipe, said chamber permanently open at its lower end to receive the water, and valveless connections between the pressure-chamber and an independent source of compressed air at one end, and with the water at the other end, whereby the head or normal level of the water in the well and the pressure of air from the tank will always oppose each other in the pressure-chamber, causing them to pulsate above and below the lower end of the delivery-pipe, air and water escaping thereinto in 45 alternation.
- 45 8. In an air lift-pump, the combination of a delivery-pipe formed with a contracted portion near its lower end or mouth, a pressure-chamber surrounding said pipe and permanently open at its lower end to receive the liquid and supplying compressed air thereto from above in alternation with the supply of liquid, and connections between the pressure-chamber and an independent source of 50 compressed air.
- 50 In testimony whereof I hereto affix my signature in presence of two witnesses.
